Primary Examiner — Jae Liang*Assistant Examiner* — Royner Mendoza*(74) Attorney, Agent, or Firm* — Vorys, Sater, Seymour
and Pease LLP(57) **CLAIM**

The ornamental design for a part of container, as shown and described.

DESCRIPTION

FIG. 1 is a perspective view of part of container;

FIG. 2 is a rear view thereof;

FIG. 3 is a right side view thereof;

FIG. 4 is a left side view thereof;

FIG. 5 is a front view thereof;

FIG. 6 is a top view thereof; and,

FIG. 7 is a bottom view thereof.

The broken lines in the figures form no part of the claimed
design.**1 Claim, 3 Drawing Sheets**| (56)	References Cited
